UNITED STATES PATENT OFFICE.

MICHAEL GRIFFIN, OF WEYMOUTH, MASSACHUSETTS, ASSIGNOR TO JOHN W. HART, OF SAME PLACE.

SOLE-CHANNELING MACHINE.

SPECIFICATION forming part of Letters Patent No. 234,272, dated November 9, 1880.

Application filed July 26, 1880. (No model.)

To all whom it may concern:

Be it known that I, MICHAEL GRIFFIN, of Weymouth, in the county of Norfolk and State of Massachusetts, have invented certain Improvements in Machines for Channeling Inner Soles for Sewed Shoes, of which the following is a full, clear, concise, and exact description, reference being had to the accompanying drawings, in which—

10 Figure 1 is an elevation, and Fig. 2 a bottom plan, of such parts of a channeling-machine as are necessary to illustrate my invention. Figs. 3 and 4 are perspective views of one set of knives. Figs. 5 and 6 show two 15 forms of knives for giving the vertical cut necessary to completely sever the strips partially cut from the sole by the knives shown in Figs. 3 and 4. Fig. 7 is a partial cross-section, enlarged, of an inner sole channeled in my machine.

20 In the drawings, A represents the head of the machine, and B the feed-roll, these parts being as usual in these machines.

The knives are marked $a a'$ and $b b'$ and 25 the pressers $d d'$. It will be understood by all skilled in the art that the sole is fed forward by the rotation of roll B, in connection with a second roll or other support. (Not shown in the drawings.)

30 Two strips, f , are cut out from the inner sole, leaving a ridge, g , near and nearly parallel with the edge, as shown in Fig. 7, to prepare it for use in sewed boots and shoes; and the object of my invention is to do this more rapidly and with less expense than heretofore, 35 more resembling hand-work.

In my machine the knives $a a'$ cut vertically

into the sole to the proper depth, these two cuts being parallel and forming the sides of ridge g . The other two knives, $b b'$, are set so 40 that they complete the cutting-out of the strips f , and it is this arrangement of the roughened feed wheel or roll B of a channeling-machine between the vertical knives $a a'$ and the inclined knives $b b'$, set to cut out the two strips 45 f from the surface of the sole and to leave the ridge g nearly parallel with the sole-edge, that constitutes my invention.

The vertical knife may be formed in one piece with its stock, as in Fig. 6, or may be a 50 blade held in a divided stock, as in Fig. 5.

Heretofore in all machines known to me for doing this work a knife with an angular cutting-edge was used. This knife was difficult to keep sharpened properly, and unless in perfect order was apt to tear the inner sole. In my machine each knife cuts easily and is readily sharpened, as it is a simple blade mounted upon a suitable stock to enable it to be held firmly in the machine.

60 I am aware that it is not broadly new to employ two separate cutting-blades.

What I claim as my invention is—

In a channeling-machine, the roughened feed-roll B, arranged between the two pairs of 65 knives $a b$ and $a' b'$, each pair arranged to cut out a strip, f , from the surface of the sole, and the whole operating to form the ridge g by four distinct cuts, as described.

MICHAEL GRIFFIN.
